CLAIM

The ornamental design for a trash can shoe, as shown and described.

DESCRIPTION

FIG. 1 is a top perspective view of a trash can shoe showing the new design.

FIG. 2 is bottom plan view thereof, with the other side view being a mirror image thereof.

FIG. 3 is a side plan view thereof, with the other side view being a mirror image thereof.

FIG. 4 is a front plan view thereof, with the other side view being a mirror image thereof; and,

FIG. 5 is a side plan view shown in a condition of use. The broken lines showing the trash can in FIG. 5 depict environment that form no part of the claimed design.
